ATTORNEY.

UNITED STATES PATENT OFFICE

98,476

DESIGN FOR A STOCKING

Otto Eugene Huber, Reading, Pa., assignor to The
Narrow Fabric Company, West Reading, Pa.,
a corporation of Pennsylvania

Application December 23, 1935, Serial No. 60,235

Term of patent 14 years

To all whom it may concern:

Be it known that I, Otto Eugene Huber, a citizen of the United States of America, residing at Reading, in the county of Berks and State of Pennsylvania, have invented a new, original, and ornamental Design for a Stocking, of which the following is a specification, reference being had to the accompanying drawings, forming part thereof.

Figure 1 discloses a stocking, embodying my ornamental design, and to which no tension has been applied; the elastic portion in the stocking top comprising the characteristic feature of the design.

Fig. 2 discloses the portion of my stocking, defined within the block A of Fig. 1, and to which no tension has been applied.

Fig. 3 discloses the portion of my stocking, defined within the block A of Fig. 1, and as it appears when subjected to tension substantially equivalent to that incident to normal usage.

Figure 1 is a showing of a stocking reduced to approximately one-half normal size.

Figures 2 and 3 are showings of a portion of the stocking enlarged approximately one and one-half times normal size, but which will approximate full size upon reduction for printing.

I claim:

The ornamental design for a stocking as shown and described.

In testimony whereof I affix my signature.

OTTO EUGENE HUBER.
